Fig. 1

Fig. 2

*Fig. 5**Fig. 3**Fig. 4*

FIG. 1 is a front perspective view of a cart for basketballs and similar objects, with the gate in its raised, locked position, showing my new design;

FIG. 2 is a front perspective view thereof, but with the gate in its lowered, unlocked position;

FIG. 3 is a front elevational view thereof, with the gate in its raised, locked position;

FIG. 4 is a rear elevational view thereof;

FIG. 5 is a side elevational view thereof; and

FIG. 6 is a top plan view thereof.

The broken line representations of basketballs in FIGS. 3-6 are for purposes of illustration only.

I claim:

The ornamental design for a cart for basketballs and similar objects, substantially as shown and described.
